UNITED STATES PATENT OFFICE.

ALBERT PRIES, OF ST. LOUIS, MISSOURI.

DESIGN FOR A BATH-TUB FOOT.

SPECIFICATION forming part of Design No. 22,331, dated April 4, 1893.

Application filed December 9, 1892. Serial No. 454,669. Term of patent 14 years.

To all whom it may concern:

Be it known that I, ALBERT PRIES, a citizen of the United States, residing at St. Louis, in the State of Missouri, have invented a certain new and original Design for Bath-Tub Feet; and I do hereby declare the following to be a full, clear, and exact description of the invention, such as will enable others skilled in the art to which it appertains to make and use the same.

My design relates to bath tub feet and the leading feature of my design consists of the foot representing an animal's paw armed with sharp claws with leg and scroll ornaments constituting the upper portion.

The accompanying drawing illustrates my design and as will be seen by reference thereto the feet proper upon which the bath tub is supported are made in imitation of the paw of an animal armed with sharp claws, B,

being the paw and C, C, C, the claws. Above the portion B, the foot extends up to or nearly up to the rim of the bath tub, growing somewhat narrower from a point just above the paw to the upper end, and this upper portion 25 of the foot is of fanciful configuration comprising a number of artistically disposed lines, scrolls, leaves, &c., the particular configuration of the upper part of the foot being variable without departing from the spirit of 30 my invention.

What I claim is—

The design for a bath tub foot herein shown and described.

In testimony whereof I affix my signature in 35 presence of two witnesses.

ALBERT PRIES.
